UNITED STATES PATENT OFFICE

JOHN T. TAWLKS, OF EVERETT, WASHINGTON, ASSIGNOR TO TAWLKS GRATE BAR COMPANY, A CORPORATION OF WASHINGTON

GRATE BAR

Application filed May 25, 1927. Serial No. 194,108.

This invention relates to improvements in grate bars for furnaces and the like, and particularly to demountable, water cooled grate bars; it being the principal object of the invention to provide grate bars comprising dis-
5 connectible upper and lower sections that are cooled by a circulation of water through pipes that are disposed between the bar sections but which are entirely separate therefrom so that 10 the sections may be easily and quickly demounted for repair or replacement.

Other objects of the invention reside in the various details of construction and combination of parts as is hereinafter described.
15 In accomplishing these objects of the invention, I have provided the improved details of construction, the preferred forms of which are illustrated in the accompanying drawings, wherein—

20 Figure 1 is a perspective view of a part of a furnace grate formed by water cooled grate bars that are constructed in accordance with this invention; the top section of the forward bar being removed for better illustration.

25 Figure 2 is a plan view of the lower section of a grate bar as assembled with the water cooling pipe.

Figure 3 is a perspective view showing ends of the upper and lower sections of a grate 30 bar.

Figure 4 is a transverse section of the bar, taken on the line 4—4 in Figure 2.

Figure 5 is a partial plan view of an alternative construction.

35 Referring more in detail to the drawings—
1 and 2 designate opposite side walls of a furnace fire box, by which a grate, designated by reference numeral 3, is supported; the grate consisting of a plurality of bars 40 that are disposed closely together in parallel relation and supported at their ends on shoulders 4 formed by the walls.

Each of the grate bars comprises a lower, or base, section 5 and an upper, or cap, section 6 and these, preferably, are of the same dimensions with respect to width and length and are fitted flatly together and held in assembled relation by means of screws 7 extended therethrough. The upper sections 50 are also provided at their ends with down-

wardly projecting lugs 8 adapted to seat within notches, or recesses, formed in the ends of the lower sections as a means of retaining the parts against displacement.

The upper sections of the bars may be flat 55 on top or may have the top surfaces slightly crowned, as illustrated, and, extending centrally of and in the longitudinal direction of the bars, are rows of apertures 9 and likewise the adjoining edges of the bars are recessed 60 to provide openings 10 for the passage of air through the grate.

Disposed between the upper and lower sections of each bar is a pipe coil 12 for the circulation of water as a cooling medium. 65 The coil, as shown, is of an elongated, U-shaped form extending nearly the length of the bar, and is seated within similarly formed cooperating channels 13 and 14 in the adjacent faces of the bar sections in order that the 70 sections will not be held in spaced relation by the pipe.

At one end of the bar the ends of the pipe coil are turned downwardly through recesses 75 15 and 16 in the end of the lower bar section and are connected, respectively, with cold water supply and lead pipes 17 and 18; the connections with the latter pipes including cut-out valves 19 and 20.

In Figure 5 I have illustrated a construction in which the water pipes enter and leave the bar through notches on its side edges instead of at the ends. This avoids weakening the end of the bar where strength is desired.

80 In the construction illustrated, it is readily apparent that the cooling coil of each bar receives a flow of cold water from the supply pipe and this passes through the coil to the drain pipe from which it may be discharged, or may be pumped into the boiler; the water being slightly heated.

85 A bar cooled in the above manner will last many times longer than an uncooled bar; they will stand up under greater heat and will require practically no cleaning, thus reducing the expense of upkeep and the time during which boilers are kept out of commission for repair or cleaning. Such bars 90 also give increased combustion as the air 100

ducts do not become clogged with fused material.

It is to be noted also that each bar has an independent circulation of water and that
5 the circulation may be cut off from any bar when it is desired to disconnect and dismount the latter for replacement. Dismounting of the bars may be accomplished without the removal of the coil or its disconnection from
10 the circulating pipes.

It is evident that the bars may be made in any suitable form, in one piece or cast in sections; that the coils may be varied in form and arrangement; that intake and outlet may
15 be at the ends or anywhere between, and water introduced from the sides or from above or below the bars and accordingly I claim the right to vary the form and arrangement of the parts in accordance with
20 the principle of the invention.

Having thus described my invention, what I claim as new therein and desire to secure by Letters-Patent, is:

A grate construction comprising in combination with water supply and return pipes, a plurality of base bars arranged in parallel edge to edge relation, a plurality of cap or cover bars removably fitted to said base bars respectively and likewise arranged in edge
25 to edge relation and together forming the top surface of the grate; each of said base bars and its cap bar being provided in their adjacent surfaces with grooves together forming a channel that opens at its ends adjacent one end of the bar set, and a plurality
30 of pipe loops, connected with the water supply and return pipes to afford circulation through said loops, disposed within said channels between said base and cap bars but
35 having no fixed connection with any part thereof and permitting of disassembly and removal of the bars without disturbing the loop or its connections.

Signed at Everett, Washington, this 18th
45 day of May, 1927.

JOHN T. TAWLKS.
